UNITED STATES PATENT OFFICE.

JAMES EBENEZER TONKIN, OF CAMPERDOWN, NEAR SYDNEY, WILLIAM AMES, OF NORTH SYDNEY, NEAR SYDNEY, AND WILLIAM EUGENE HORT NICOLLE, OF BEECROFT, NEAR SYDNEY, NEW SOUTH WALES, AUSTRALIA.

MEANS FOR SECURING THE FASTENINGS OF RAILWAY OR TRAMWAY RAILS AT THE JOINTS.

SPECIFICATION forming part of Letters Patent No. 760,586, dated May 24, 1904.

Application filed February 24, 1903. Serial No. 144,811. (No model.)

To all whom it may concern:

Be it known that we, JAMES EBENEZER TONKIN, residing at Missenden Road, Camperdown, near Sydney, WILLIAM AMES, residing at West street, North Sydney, near Sydney, and WILLIAM EUGENE HORT NICOLLE, residing at Beecroft, near Sydney, in the State of New South Wales, Australia, have invented a certain new and useful Improvement in Means for Securing the Fastenings of Railway or Tramway Rails at the Joints; and we do hereby declare the following to be a full, clear, and exact description of the invention, such as will enable others skilled in the art to which it applies to make and use the same.

The object of this invention is to provide a useful contrivance which when adapted to the fastenings of railway and tramway rails will so secure them as to prevent their possible displacement or disarrangement by any of the ordinary influences which are known to operate disadvantageously in the working of railway rolling-stock and which necessitates careful daily supervision to insure immunity from danger or damage. The parts most affected by vibration or jarring may be retained by this device in their correct relative positions for an indefinite period, and thereby the frequent visits of inspection by responsible persons are rendered unnecessary. To minimize cost of adaptation, the existing parts, comprising fish-plates and bolts, are utilized, as in railway practice, although a special form of fish-plate is hereinafter described suitable for the purposes set forth.

In the accompanying drawings, which form part of this specification, Figure 1 shows separately the serviceable parts of the invention. Fig. 2 is a sectional plan showing the same parts in combination secured. Fig. 3 is an end view to illustrate the spring-catch. Fig. 4 shows in perspective the jointed rail with locking-plate removed. Fig. 5 is a similar view to Fig. 4 with lock-plate in position. Fig. 6 shows in plan the fish-plate varied in form to receive a lock-plate with turned ends.

Fig. 7 shows in plan the fish-plate varied in form to receive a straight lock-plate. Fig. 8 is an ordinary fish-plate with supporting-pins to carry a lock-plate.

The grouped parts (shown in Fig. 1) consist of the fish-plate A, the clamping-plate B, and the lock-plate C. The holes D are common to all fish-plates and are fitted with the usual bolts E. (Vide Figs. 2, 4, 5, 6, and 7.) The clamping-plate B is similarly pierced to correspond with the fish-plate A and is provided for the purpose of forthwith accommodating this invention to existing railway-lines, so as to minimize the cost of its immediate adaptation; but the invention further provides for converting a fish-plate into a clamping-plate, so that the lock-plate C may be supported thereon, in which case the folded ends F, shown on the plate B, will, as in Fig. 7, be formed upon the fish-plate A. The clamping-plate would in these circumstances be held in position, as shown in Figs. 2, 5, and 7, it being merely a flat bar having the gaps G to secure the nuts H. This plate is prevented from rising by the outward set or spring-catch I, formed on the ends, (vide Fig. 3,) it being likewise retained by a similar catch J, formed at the bottom of the folded ends F. These catches have inclined faces which wedge against each other, but do not lock by square shoulders or equivalent means. This plate may consist of an angle-iron, as shown in dotted line in Fig. 1. In Fig. 6 the lock-plate C has the folded ends F, and the fish-plate A is turned outward at each end to receive it. These devices are but alternative means of accomplishing the same object under varying conditions. In Fig. 8 the fish-plate A has the supporting-pins K, which are used to retain a straight clamping-plate, such as is shown in Figs. 1, 2, 5, and 7. A gap would of course be provided at the ends of the plate, so that when dropped in position it would not only rest upon each of the nuts H, but would also be prevented by the broad heads of the pins K from loosening and falling out of position.

It is obvious that this simple appliance may be adapted to all existing forms of railway-lines, as in Fig. 1, at a minimum expense.

The method of applying the invention consists in placing the clamping-plate B upon the bolts E and then applying a compressible washer L to admit of the adjustment of the nuts, which only require to be slightly turned to accommodate them to the gaps in the locking-plate C. This plate when once placed in position between the folded ends F will effectually prevent the disarrangement of the nuts. The washers are not indispensable, as it is found in practice possible to adjust the nuts upon the fish-plate alone or upon the clamping-plate covering the fish-plate.

Having now particularly described and ascertained the nature of our said invention and in what manner the same is to be performed, we declare that what we claim is—

1. In combination with a pair of railway-rails and their fastening-bolts, a pair of plates, which extend across the joint of the rails and overlap at their ends and are provided with means for preventing the nuts of the said bolts from turning, the inner plate being provided with holes, through which the said bolts pass,

the outer plate being vertically removable, and the overlapping ends of the plates being provided with locking parts, having inclined faces in contact with each other substantially as set forth.

2. In combination with a pair of railway-rails and their fastening-bolts, a pair of plates which extend across the joint of the said rails and are provided with means for preventing the nuts of the said bolts from turning, the inner plate being provided with holes through which the said bolts pass and having its ends F bent forward around and front of the ends 40 of the outer plate and the said ends and the proximate parts of the outer plate being provided with locking parts J I having inclined faces substantially as set forth.

In testimony whereof we have hereunto affixed our signatures in presence of two witnesses.

JAMES EBENEZER TONKIN.
WILLIAM AMES.
WILLIAM EUGENE HORT NICOLLE.
